CORE DRILL CONSTRUCTION

John H. Howard, Huntington Park, and Alfred C. Catland, Alhambra, Calif.; said Catland assignee to Globe Oil Tools Company, Los Nietos, Calif., a corporation of California

Application January 14, 1936, Serial No. 59,076

5 Claims. (Cl. 255—72)

The invention relates to well drilling tools and relates more particularly to a core drill construction. A general object of this invention is to provide a core drill embodying an improved, dependable and simple valve means for the inner barrel of the drill.

Another object of this invention is to provide a core drill assembly in which the valve is effectively secured to the upper end of the inner barrel without cutting threads on the inner barrel whereby the inner barrel may have a thin wall to be light in weight. In core drills having inner barrels and especially in core drills having rotatably supported inner barrels it is very desirable to make the inner barrels as light in weight as possible. It has been the usual practice to thread the valve to the upper end of the inner barrel of a core drill, which has made it necessary to form the inner barrel with a relatively thick wall to carry the threads. In accordance with the present invention the valve is dependably secured to the inner barrel without employing threads so that the inner barrel may be very light in weight.

Another object of this invention is to provide a core drill construction in which the valve may be easily and quickly applied to and removed from the inner barrel when the inner barrel is removed from the outer barrel and in which the valve cannot become displaced when the tool is assembled for operation.

A further object of this invention is to provide a core drill construction of the character mentioned that is simple and very inexpensive.

The various objects and features of our invention will be fully understood from the following detailed description of a typical preferred form and application of the invention, throughout which description reference is made to the accompanying drawing, in which:

Fig. 1 is a side elevation of a core drill embodying the present invention with a portion of the outer barrel broken away to show the valve and the upper part of the inner barrel in side elevation. Fig. 2 is an enlarged vertical detailed sectional view of the valve being a view taken as indicated by line 2—2 on Fig. 3 and Fig. 3 is a horizontal detailed sectional view taken as indicated by line 3—3 on Fig. 2.

The core drill in which the present invention is embodied includes, generally, an outer barrel 10 carrying a suitable core cutting head or bit 11, an inner barrel 12 within the outer barrel 10 for receiving the core, a valve 13 for the upper end of the inner barrel 12 and means 14 for removably securing the valve 13 to the inner barrel 12.

The outer barrel 10 is an elongate tubular structure adapted to be connected with the lower end of a string of drill pipe. A suitable sub 15 may be provided on the upper end of the outer barrel 10 to facilitate its connection with the drilling string. The particular sub 15 illustrated has a tapered screw threaded pin 16 for cooperating with a socket in the lower end of the drilling string. The head or bit 11 is shown secured to the lower end of the outer barrel 10 by a connecting member or sub 17. The bit 11 has cutting means for making an annular cut in the earth formation to leave a core for reception in the inner barrel 12. In accordance with the broader aspects of the invention, the outer barrel 10 may be provided with any suitable form of cutting head or bit. The particular bit 11 shown in the drawing has circumferentially spaced blades 18 for making an annular cut in the formation. Ports 19 are provided in the bit 11 at points between the blades 18 for discharging the circulation fluid.

The inner barrel 12 is an elongate tubular assembly or structure arranged longitudinally in the outer barrel 10 to receive the core. The inner barrel 12 may be supported at its lower end in the bit 11 or the sub 17. The present invention is not concerned with the details of the means for supporting the inner barrel 12 and details of the mounting means for the inner barrel have been omitted from the present disclosure. The inner barrel 12 may have comparatively thin walls to be light in weight and to receive a larger core. In the particular construction shown in the drawing, a tubular extension 20, having a relatively heavy wall, is welded to the upper end of the inner barrel 12. It is to be understood that this extension 20 is not essential. The inner barrel 12 is spaced from the interior of the outer barrel 10 to leave an annular passage 21 for conducting the circulation fluid downwardly to the discharge ports 19.

The valve 13 is provided on the upper end of the inner barrel 12 to prevent the downwardly flowing circulation fluid from entering the upper end of the inner barrel and is operable to permit the discharge of fluid from the inner barrel 12 as it is displaced by the entering core. Divisional application Serial No. 88,991 specifically describes and claims a valve similar to the valve 13. The valve 13 includes a body 22 whose lower portion is entered in the longitudinal opening 23 of the inner barrel 12 and whose upper portion projects beyond the upper end of the inner barrel. An annular downwardly facing shoulder 24 is provided on the valve body 22 to seat downwardly

against the upper end of the inner barrel or, as shown in the drawing, to seat downwardly against the upper end of the inner barrel extension 20. A central socket or opening 25 extends upwardly in the valve body 22 from its lower end and communicates with the opening 23 of the inner barrel. The upper portion of the valve body 22 which extends upwardly from the inner barrel or the inner barrel extension 20 is shaped to divert the downwardly flowing circulation fluid. In the preferred construction, this projecting cage portion of the valve body 22 is hemispherical as illustrated. The projecting upper portion of the valve body 22 is chambered having a valve chamber 26. Circumferentially spaced lateral ports 27 extend outwardly from the chamber 26 and may have comparatively large mouths at the exterior of the body for communicating with the fluid space in the outer barrel 10.

20 The valve body 22 has a central opening 23 of reduced diameter connecting the opening 25 with the chamber 26. A hardened replaceable valve seat 30 is provided in the opening 28. It is preferred to thread the seat 30 in the opening 28 and the invention provides a simple effective means for positively locking the valve seat 30 against unthreading. Notches 31 are provided in the lower end of the valve seat 30 and following the proper threading of the seat in the opening 30 28, a bar 32 is inserted in the notches 31 and is then welded to the body 22. The bar 32, cooperating with the notches 31 and welded to the valve body as at 33, dependably prevents unthreading and displacement of the valve seat 30. The bar 35 32 in addition to locking the seat 30 in place, forms a strainer for preventing large objects from passing upwardly through the seat 30. The valve 13 includes a valve proper or ball 34 arranged in the chamber 26 to cooperate with the upper end 40 of the seat 30. When the ball 34 seats downwardly against the seat 30 it effectively prevents the entrance of the circulation fluid to the upper end of the inner barrel 12.

The means 14 for removably securing the valve 45 13 to the inner barrel 12 is an important feature of the invention. The means 14 includes one or more latches 35 on the valve body 22 for cooperating with the inner barrel 12. In the particular form of the invention illustrated, there are 50 four latches 35 equally spaced about the valve body 22. The upper ends of the latches 35 are pivotally connected with the valve body 22 above the upper end of the inner barrel 12 or the inner barrel extension 20. Webs 36 occur on the valve body 22 between the mouths of the ports 27 and recesses 37 are provided in the outer sides of the webs 36. The upper portions of the latches 35 project into the recesses 37 and pivot pins 38 are carried in openings in the webs 36 and extend 60 through openings in the latches 35 to pivotally connect the latches with the valve body 22. The latches 35 are comparatively long and are adapted to extend longitudinally or downwardly at the exterior of the inner barrel or the inner barrel extension 20. Inwardly projecting lugs 39 are provided on the lower ends of the latches 35. The lugs 39 are preferably round or substantially cylindrical to extend through lateral openings 40 in the wall of the inner barrel 12 or 70 the inner barrel extension 20. Circumferentially spaced openings or sockets 41 are provided in the exterior of the valve body 22 to communicate with the openings 40. The lugs 39 of the latches 35 are adapted to extend through the openings 40 75 and project into the sockets 41. The latch lugs

39 and the openings 40 and the sockets 41 receiving the latch lugs may be comparatively large in diameter as illustrated in Fig. 2 of the drawing. The cooperation of the latch lugs 39 with the openings 40 and the sockets 41 dependably locks the valve body 22 against displacement from the inner barrel 12.

5 The latches 35 just described are proportioned so that their outer sides have slight clearance in the outer barrel 10. This relationship between the latches 35 and the outer barrel 10 positively prevents the release or outward pivoting of the latches 35 when the inner barrel 12 with its valve 13 is assembled or positioned within the outer barrel. The latches 35 also act as bumpers or centralizing ribs for maintaining the upper portion of the inner barrel centralized in the outer barrel 10. In assembling the valve 13 on the inner barrel 12, the valve body 22 may be arranged on the upper end of the inner barrel or the inner barrel extension 20 to have its shoulder 24 properly cooperate therewith. Following the seating of the valve body 22, it may be turned to bring the sockets 41 in proper alignment or register with the openings 40. The latches 35 may then be 20 swung or pivoted to enter the lugs 39 in the openings 40 and the sockets 41. The inner barrel 12 may then be assembled in the outer barrel 10.

25 In the operation of the core drill, the outer barrel 10 is connected with the lower end of the drilling string and the string is rotated and fed downwardly in the well to cause the bit 11 to cut into the earth formation. The circulation fluid is pumped downwardly through the drilling string to flow downwardly through the 30 passage 21 and discharge from the ports 19. The valve or ball 34 cooperating with the seat 33 effectively prevents this downwardly flowing fluid from entering the upper end of the inner barrel. As the core formed by the bit 11 enters 40 the inner barrel 12, fluid may be displaced from the inner barrel causing the ball 34 to rise from its seat 30.

35 The latches 35 dependably and securely attach the valve body 22 to the inner barrel 12. The 45 lugs 39 of the latches 35 fitting in the openings 40 and the sockets 41 positively prevent longitudinal movement and displacement of the valve body 22. It will be understood that the cooperation of the lugs 39 with the openings 40 and the 50 sockets 41 may relieve the pivot pins 38 of all stresses. The latches 35 fitting the outer barrel 10 with only slight clearance cannot pivot outwardly sufficiently to allow their lugs 39 to move from the sockets 41. Accordingly, as long as the 55 inner barrel 12 remains in the outer barrel 10 its valve 13 cannot become displaced. Following the removal of the inner barrel 12 from the outer barrel 10 at the termination of the drilling operations, the valve 13 may be easily removed from 60 the inner barrel 12 by pivoting the latches 35 upwardly. The valve 13 with its latches 35 is a simple inexpensive structure. The openings 40 and the sockets 41 for receiving the latch lugs 39 may be simple bores.

65 Having described only a typical form and application of our invention, we do not wish to be limited or restricted to the specific form and application herein set forth, but wish to reserve to ourselves any modifications or variations that may appear to those skilled in the art or fall within the scope of the following claims.

70 Having described our invention, we claim:
1. In a core drill, a barrel having an opening 75 in its wall, a valve removably arranged in the

barrel and exposed at its upper end, there being a lateral opening in the valve, a latch pivoted on the exposed end of the valve, and a part on the latch cooperating with said openings to secure the valve to the barrel.

5. 2. In a core drill, an outer barrel, an inner barrel arranged in the outer barrel and having an opening in its wall, a body in the upper portion of the inner barrel having an opening registering with the first named opening, and a pivoted latch cooperating with the openings to attach the body to the inner barrel and proportioned to be retained in the openings by the outer barrel.

10. 3. In a core drill, an outer barrel, an inner barrel arranged in the outer barrel and having an opening in the wall, a body in the upper portion of the inner barrel having an opening registering with the first named opening, and a latch pivoted on the body and retained in cooperation with the openings by the outer barrel.

15. 4. In a core drill, an outer barrel, an inner barrel arranged in the outer barrel and having

an opening in its wall, a valve for the inner barrel comprising a body in the upper portion of the inner barrel having an opening registering with the first mentioned opening, a latch shiftably connected with the body and rather closely fitting within the outer barrel, and a part on the latch cooperating with the openings and held therein by the fit of the latch in the outer barrel.

20. 5. In a core drill, an outer barrel, an inner barrel arranged in the outer barrel and having circumferentially spaced openings in its wall, a valve for the upper end of the inner barrel comprising a body arranged in the upper portion of the inner barrel and having sockets communicating with the openings, latches pivoted to the body to depend between the inner barrel and the outer barrel, and parts on the latches cooperating with the openings and sockets and held therein by the cooperation of the latches with the outer barrel.

20

JOHN H. HOWARD.
